United States Patent

Des. 238,627

Patented Feb. 3, 1976

238,627

COMBINED BELT AND POCKET

Ruth G. Lewis, 1721 Dorchester Drive,
Oklahoma City, Okla. 73120

Filed Dec. 27, 1973, Ser. No. 428,704

Term of patent 14 years

Int. Cl. D2—07

U.S. Cl. D2—381

FIG. 2

FIG. 1

FIG. 3

FIG. 1 is a front perspective view of a combined belt and pocket showing my new design;

FIG. 2 is a rear perspective view thereof; and
FIG. 3 is a top plan view.

I claim:

The ornamental design for a combined belt and pocket, as shown.
